HAND TOOL

Clarence M. Kimball, Royal Oak, Mich.

Application June 2, 1933, Serial No. 673,951

12 Claims. (Cl. 164—83)

My invention relates to hand tools. It has to do particularly with a device for making various types of cuts in relatively soft materials, such as fiber composition insulation or wall board, 5 cardboard, soft wood, linoleum, and rubber floor coverings. With the use of my improved cutting tool, materials of the type mentioned may be sliced or cut into desired size, the edges may be bevelled, and the surface relieved or grooved 10 to effect an infinite variety of ornamental designs and shapes for decorative purposes.

A better understanding of the invention will be had upon reference to the accompanying drawings, wherein Figure 1 is a perspective view 15 of the assembled knife holder viewed on its side to show the bottom or work engaging surface. Figure 2 is a detailed perspective view showing two separated parts, which together comprise one-half of the tool body. Figures 3 and 4 are 20 sectional views taken on lines 3—3 and 4—4, respectively, of Figure 1. Figure 5 is a perspective view, and Figure 6 an end elevation of the tool, having mounted thereon an adjustable guide and a knife blade, as arranged for a beveling 25 operation. Figures 7 and 8 are perspective and elevational views, respectively, of the tool carrying spacer plates on its underside, and a pair of knives for performing a relatively shallow angular grooving operation. Figures 9 and 10 30 illustrate the mounting of a knife when a substantially semi-circular groove is to be cut. Figure 11 is an end elevation showing a knife blade arranged for slicing or severing. Figure 12 shows 35 in perspective, an attachment of an adjustably spaced guide. Figure 13 is another end elevation and illustrates an arrangement of knives for deep grooving. Figure 14 illustrates in perspective, an attachment which permits the formation of circular cuts, and Figure 15 is an end 40 view of the tool with the knife blades set for a still different type of groove. Figure 16 is a detail perspective view of a support for the free edge of the blade.

Referring specifically to the drawings, the knife holder is preferably in the form of a substantially rectangular block comprising in the main, a pair of longitudinally split complementary sections 1 and 2, having their mating faces extending in the 45 general direction of tool movement and in a plane normal to the underside or work engaging surface of the block. The outer side of each block section is preferably provided near its upper end with a recessed or indented portion 3 to facilitate the grasping of the tool in the op-

erator's hand, as is more particularly illustrated in Figure 12.

Adjacent opposite ends of the holder, the section 1 is provided with a tapped opening 4 to receive a clamping screw or stud 5, which passes through a counterbored opening 6, provided in the body section 2 aligned with the threaded openings 4, such screws serving to adjustably hold the sections together. Intermediate the screw receiving openings 6 each block section is provided on its mating face with a flat knife clamping surface as seen in Figure 2. Similar flat clamping surfaces extending longitudinally of the tool are formed along both sides of the split block near its bottom and present a pair of oppositely inclined or divergently disposed faces, which cooperate with flat clamping faces 7 of a pair of triangular sectioned knife holding blocks or clamping elements 8 and 9, respectively. Each triangular block is secured in place by a pair 10 of longitudinally spaced screw studs 10, threadedly engaged with suitable openings in bosses 11, formed as a part of the main block sections, the screw heads being seated within counterbored openings 12 in the triangular blocks. To facilitate access to the assembly stud 5 without removal of either triangular block, the block 9 may be provided with an enlarged opening 13 aligned with the opening 6, as shown more particularly in Figure 3.

In the interest of light weight, it is proposed to cast the block sections from aluminum or other suitable material, and to further reduce weight and cost, the main block castings may comprise thin walled shells, which when assembled will 30 provide a hollow interior.

With the tool thus described, there are provided three distinct pairs of knife clamping surfaces. In other words, knife blades may be removably secured between any one or all or any 40 various combination of the mating surfaces on the complementary main blocks 1 and 2, the triangular block 8 of the main block 1, and the triangular block 9 and the main block 2. Such knives may, for convenience, consist of thin wafers, and it may be said, incidentally, that certain safety razor blades, now on the market, serve the purpose remarkably well. These knife blades being mounted directly in the block, which in turn is held directly in the operator's hand, it will be 45 subjected to the direct thrust or pressure exerted by the hand as the tool is moved over the work surface.

When a single blade is inserted between the main block sections 1 and 2, as is illustrated in 55

Figure 11, the knife will sever the work in a plane normal or perpendicular to the work surface. When this or any of the other operations of which the cutting tool is capable is performed, 5 a suitable straight edge may, if desired, be employed for engagement with a lateral face of the tool to guide the same. If in addition to the use of the knife blade illustrated in Figure 11 a blade or blades, is or are, also clamped by the triangular blocks, the tool, besides severing the work, 10 will cut or bevel an edge or edges at the same time that the slicing operation takes place. It may be said here, that when more than one blade is used at the same time the blades should be 15 arranged in longitudinally spaced relation so as not to interfere with one another.

When an edge of the work is to be bevelled, a single knife blade may be clamped between the inclined surfaces of one of the triangular blocks 20 and the main block section, as is illustrated in Figures 5 and 6. For conveniently guiding the tool, use may be made of a guide 14, provided with end enlargements 15 presenting a guiding surface along one side as at 16. The guide is also 25 provided with a pair of open ended slots 17 for slidably receiving set screws 18, threadedly engaged within openings 19 in one or the other of the triangular sections 8 and 9, whereby the guide element may be adjusted to and from the 30 knife edge for varying the size of the bevel. The guiding surface 16 is preferably reduced at an intermediate point and opposite the location of the knife blade to avoid the crowding of the severed portion as the knife passes through the 35 material, thus avoiding jamming of the material between the knife and the guiding surface, which would affect cutting precision.

To avoid the tendency for the knife blade to flex when an edge is being bevelled it is proposed 40 to provide as optional equipment an adjustable stop in the form of a slotted clip 14a to be mounted on the underside of the plate 14, as by means of a set screw, which clip has an angular leg adapted for contact with the tip of the blade 45 projecting beyond the edge of the material operated upon. Instead of making the clip as a separate piece it can be formed as an integral boss on the plate 14.

Figures 8 and 13 each show a pair of divergent- 50 ly arranged knife blades for making a V-groove, the groove in the case of Figure 8 being of less depth than that of Figure 13, due to the use of spacer plates 20 mounted on the underside of the tool for engagement with the work. As shown in 55 Figure 7, these spacer plates may be anchored by suitable attaching screws or studs 21 threaded within the before mentioned openings 19. Near opposite ends, these spacer plates are of reduced width, as at 22, so as not to obstruct access to the attachment studs 19. It will be noted, in 60 addition, that Figure 7 illustrates the longitudinal spacing of the knife blades as suggested heretofore.

For making a semi-circular groove in the work 65 surface, and also a parti-circular bevelled edge, it is proposed to provide a special blade having a reversely bent or curved intermediate portion with opposite ends extending at an angle to each other substantially corresponding to the angular 70 relation existing between the divergent clamping surfaces of the blocks 1 and 2 so that these ends may be clamped in place with the semi-circular intermediate portion extending below the base 75 of the tool for cutting engagement with the work.

A special blade of this character is indicated at 23 in Figures 9 and 10.

The guide element 14, heretofore described, 5 may also be employed when a surface cut is to be made at a given distance from the edge of the work, by mounting the guide on the tool through a suitable spacer device. An arrangement for this purpose is illustrated in Figure 12, which shows a pair of rods 24 threaded at one end in tapped openings 25 in the block and extending 10 slidably through openings 26 in the guide 14. For holding the guide in the given position of adjustment, set screws 27 may be extended through tapped openings 28 into engagement with the rods 24. For convenience, the rods 24 15 may be made in detachable sections having suitable coupling joints, as for example, a sleeve 29 threaded to each section. It will be obvious, of course, that any required number of rod sections may be utilized, depending upon the spacing required. 20

In order that the tool may be used for making circular cuts, I propose the use of a radius arm 30, shown in Figure 14, for detachable engagement 25 with the knife holder. This radius arm may consist of an ordinary wooden stick having a number of regularly spaced openings 31, through any one of which a nail or other pivot pin may be passed for swingably anchoring the radius arm to the work. Projecting laterally at each 30 side of the arm 30 are a pair of projections or lugs 32 for detachable pivotal connection with a pair of angle brackets 33, the base legs of which may be adjustably secured by set screws 34 passing through elongated openings 35 therein, and 35 into threaded engagement with holes 36 of the tool block. In order that a quick detachment of the tool from the radius arm may be effected, the angle brackets 33 are each provided with an open ended slot 37 inclined outwardly and adapted to receive the pivot lugs 32. Due to this inclined arrangement of the slots, and because the end of the radius arm 30 contacts with the tool, accidental disengagement of the parts is prevented. To effect a separation, the tool must be 40 swung clear of the adjacent end of the arm 30 about the lugs 32 in order to clear the slots of the lugs. To mount the tool, a reverse procedure is followed. When a circular groove is to be made, 45 the radius arm is first mounted on its pivot pin and then the angle brackets 33 engaged with the pivot lugs 32 and simultaneously with the application of downward pressure on the tool, to move it into engagement with the work, the tool is 50 swung by the hand about the center pivot pin to initiate the cut as the knife contacts with and digs into the surface. For best results, it is 55 desirable that the knife blade be mounted as near as possible to the center line of the bar 30 so that it will not be out of tangential relation with the 60 swing and receive undue stress.

While a semi-V-groove is illustrated being cut in Figure 14, it will be understood that any of the cuts previously described may be made when the circling attachments are employed. To better 65 illustrate the formation of a semi-V-groove, Figure 15 of the drawings has been incorporated, and it shows one knife blade clamped between one of the main blocks and a second blade between one of the triangular blocks and the main block section. 70

While the above description has referred to the use of two or more blades at the same time, it may be found advisable in the case of relatively hard material to use each blade separately. It 75

may also be desirable to cut the material lightly at first and increase the depth of the cut on a second and even a third stroke, in order to produce a straight, accurate, and clean cut. However, the tool may be used in various numbers of ways, depending upon the conditions involved, the only necessity being that an even pressure be maintained on the tool at all times, and that the bottom be kept flat on the surface of the work throughout the length of the cut.

While the above description has been more or less specific as to details, it will be understood that the invention is not limited to the precise embodiment illustrated, and that various modifications may be made as come within the scope of the appended claims.

I claim:

1. A cutting tool adapted for sliding engagement with the work to be operated upon, including a hand engaging member having a pair of knife holding surfaces, extending in divergent relation to each other from the work engaging surface one of which surfaces lies in a plane normal to the work engaging surface and the other in a plane inclined thereto, and means to secure knives to the respective holding surfaces for simultaneously cutting the two sides of a V groove.
2. A cutting tool adapted for sliding engagement with the work to be operated upon, including a hand engaging member having a knife engaging surface lying in the plane of tool movement and inclined to the work engaging surface, a triangular sectioned block having a knife clamping surface cooperating with the surface of said member, and means to clamp said block to the member with the mating surfaces embracing a knife blade.
3. A cutting tool of the character described, including a longitudinally divisible sectional block adapted to be held in the hand for sliding engagement with the work in a direction longitudinally thereof, said block comprising a pair of main sections split in a plane normal to the work engaging surface to clamp a knife therebetween, and provided with divergently disposed sides, and a pair of secondary sections, one for each of said inclined sides to clamp a knife thereto.
4. A hand tool for movement over the work surface, including a longitudinally divisible sectional block, means to clamp block sections together to hold a pair of knife blades in divergent relation, and a spacer plate adapted to be removably mounted on the work engaging surface of the block to change the depth of the knife blade cut.
5. A hand tool for movement over the work surface, including a longitudinally divisible sectional block, means to clamp block sections together on lines inclined and vertically related respectively to the work engaging surface and knives inserted on said lines between the block sections.
6. A hand tool for movement over the work surface, including a longitudinally divisible sectional block, means to clamp block sections together on a line inclined to the work engaging surface to clamp a knife therebetween, a gage bar having a pair of longitudinally spaced elongated slots extending at right angles to its guid-

ing surface, and set screws removably engaged in threaded openings in the underside of one of said block sections and projected thru said elongated slots for clamping the guide bar against the bottom of the last mentioned block section in pre-selected positions of adjustment toward or away from the knife.

7. A hand tool for sliding engagement with the surface of the work, comprising a sectional block divisible along longitudinal lines and having mating surfaces of two sections extending in a plane inclined to the underside, a cutting blade clamped between said mating surfaces at a point intermediate the opposite ends of the block, a guiding element associated with the underside of the block for engagement with the edge of the work and provided with a reduced portion intermediate its ends and opposite said blade to relieve pressure on the material severed by the knife.

8. A hand tool for sliding engagement with the work surface, including a knife holding block adapted to be held in the hand, a swinging radius arm having lugs projecting from opposite sides thereof near one end, and a pair of spaced brackets extending laterally from the block and having inclined open ended slots adapted to receive said lugs and afford a pivotal connection about which the block may be swung into work engaging relation during its initial circular movement.

9. In combination, a knife holding block adapted to be held in the hand and moved over the work surface, a rigid radius arm for guiding said movement and a connection hinging the block to the end of said arm for swinging the block about said connection and into engagement with the work.

10. A hand tool for sliding engagement with the surface of the work, including a hand engaging member, a cutting blade supported thereby in a plane extending longitudinally of the member and inclined to the work engaging surface for beveling the work edge, a guide having a longitudinally extending surface for engagement with the edge of the work and being of reduced depth adjacent said knife to relieve pressure on material as the knife passes therethrough.

11. A hand tool for beveling edges, including a block adapted to be held in the hand and moved over the surface of the work with portions thereof projecting on opposite sides of the edge to be beveled, a knife blade projecting diagonally from the underside of the block away from the work engaging portion and an abutment projecting downwardly from the other of said block portions for engaging the free end of the blade.

12. A hand tool for movement over the work to make a surface cut, including a pair of divergently related knife holding surfaces extending in the general direction of tool movement, a substantially V-shaped wafer thin knife blade lying throughout its width and length in the general direction of tool movement, and having an intermediate cutting loop for severing portions of the work without displacing the same, with opposite end portions projecting from said loop in divergent relation, and means securing the opposite end portions in flat engagement with said divergently related knife holding surfaces.

CLARENCE M. KIMBALL.
